DESIGN FOR A MOULDING

Desmond J. Drischell, Baldwin, N. Y., assignor
of one-half to Jacob C. Chase, Long Beach,
Calif.

Application June 15, 1946, Serial No. 130,754

Term of patent 7 years

(Cl. D13—6)

To all whom it may concern:

Be it known that I, Desmond J. Drischell, a citizen of the United States and a resident of Baldwin, in the county of Nassau and State of New York, have invented a new, original, and ornamental Design for a Moulding, of which the following is a specification, reference being had to the accompanying drawing, constituting a part thereof in which:

Fig. 1 is a top plan view of the moulding showing my new design;

Fig. 2 is a front elevational view;

Fig. 3 is a cross-sectional view taken through the plane 3—3 of Fig. 1; and

Fig. 4 is a similar view taken through the plane 4—4 of Fig. 2.

I claim:

The ornamental design for a moulding, substantially as shown.

DESMOND J. DRISCHELL.
